LOCKED-IN OSCILLATOR CIRCUITS

Murlan S. Corrington, Camden, N. J., assignor to
Radio Corporation of America, a corporation of
Delaware

Application November 14, 1944, Serial No. 563,379

7 Claims. (CL 250—20)

1

My present invention relates generally to improved locked-in oscillator circuits, and more particularly to a novel method of, and means for, extending the lock-in range of frequency dividers of the locked-in oscillator type.

In my application Serial No. 513,371, filed December 8, 1943, I have disclosed and claimed novel circuits for receiving angle-modulated carrier waves employing a locked-in oscillator system acting as a frequency divider. These circuits were improvements on the locked-in oscillator circuit disclosed and claimed by G. L. Beers in his U. S. Patent No. 2,356,201, granted August 22, 1944.

The locked-in oscillator operation of the Beers patent was explained in the following way in my aforesaid application: The angle modulated waves, of a predetermined mean or center frequency F are applied to the input control grid of a tube of the pentagrid type. The output or plate electrode circuit is tuned to a desired subharmonic F/n , where n is a small whole number. In the illustrative embodiment described in Fig. 1 of the Beers patent the fifth subharmonic is developed across the plate circuit. The third grid of the pentagrid tube is regeneratively coupled to the plate circuit with the result that oscillations of mean frequency F/n are produced in the plate circuit. These oscillations occur even in the absence of signal voltage on the first grid. Suppose, now, that $F=4300$ kilocycles (kc.) per second, and a signal of that mean frequency is applied to the first grid. Assume, further, that the plate circuit is tuned to 860 kc. In other words, the oscillator section operates to provide subharmonic oscillations at 860 kc. The grid voltage-plate current characteristic of the pentagrid tube is nonlinear; this would be true of any other type of tube. Hence, harmonics of F/n are impressed on the oscillator grid. These harmonics which are present on the third grid from the cathode include the fourth (3440 kc.) and sixth (5160 kc.) harmonics of the oscillator current.

Hence, the signals of 4300 kc. will beat with these fourth and sixth harmonics to provide a difference frequency the same as the desired fundamental frequency of 860 kc. (the fifth subharmonic of 4300 kc.). Now, this new component (which I term the "harmonic difference component" to distinguish it from the normal oscillator current) will not, in general, have the same phase as the normal oscillator current. It, thus, is equivalent to injecting into the plate circuit an out-of-phase current. This causes the tube to

2

act in the manner of the well-known reactance tube. If the oscillator frequency is not exactly one-fifth of the incoming signal frequency, the natural frequency of the plate circuit is pulled over until the oscillator frequency is exactly one-fifth. This causes the oscillator section to "lock in" with the applied signals.

The maximum amount the natural frequency of the oscillator can be pulled over, and still be "locked-in," occurs when the harmonic difference current is 90 degrees out of phase with respect to the normal oscillator current, since this gives the maximum out-of-phase current. When the injected (harmonic difference) current is leading the normal oscillator current, the oscillator section frequency will be pulled to one side of its natural frequency (860 kc.). When the injected current is lagging, the oscillator frequency will be pulled to the other side of its natural frequency. It will be recognized that there will thus be developed in the plate circuit a frequency modulated current "locked-in" with the applied signals.

There is a limitation on the lock-in range. This arises from the fact that the amount of fourth and/or sixth harmonic on the oscillator third grid is limited. Accordingly, this limits the amount of injected current, and thus it follows that the lock-in range of the oscillator section is limited. The result is that when the deviation of the oscillator frequency exceeds approximately 20 kc. from the oscillator mean frequency (860 kc.), the oscillator suddenly "breaks out" and its frequency returns to the mean frequency value. When the oscillator is used with a frequency discriminator in a frequency modulation receiver, distortion results by virtue of this phenomenon. There are practical operating causes for the "break out" of the locked-in oscillator.

If the receiver is mistuned slightly, as is readily done in the case of frequency modulation receivers, the "break out" of the locked-in oscillator will occur on one end of the frequency swing, even for normal 75 kc. swings or deviations. If the frequency modulation ("FM" hereinafter for brevity) transmitter over-modulates, the "break out" may occur on both ends of the swing. Likewise, gradual drifts in frequency of the oscillator or discriminator can occur due to temperature or other changes during operation, thus causing mistuning and consequent "break out."

In my aforesaid application there was provided a general method of extending the lock-in range of a locked-in oscillator thereby to overcome the undesirable effects due to "break out" of the os-

cillator caused by insufficient harmonic on the oscillator grid. Specifically, there was provided a highly practical method of increasing the lock-in range of a locked-in oscillator of the type shown in the aforesaid Beers patent; the method comprising tuning the oscillator plate circuit sufficiently to one side of F/n so that it will readily lock in on one end of the frequency swing, and tuning the oscillator grid circuit sufficiently on the other side of the desired harmonic ($4F/n$ or $6F/n$) to help lock in the oscillator on the opposite end of the swing.

It is an important object of my present invention to provide a novel method, distinct from those disclosed in my aforesaid application, of increasing the lock-in range of a locked-in oscillator by adding a passive electrical network in parallel with the oscillator tuned output circuit, and adjusting the added electrical network so that the equivalent input capacity falls off at the proper rate to just keep the oscillator in tune throughout most of the operating range. A passive electrical network is one which, in contradistinction to an active network, is not a source of electrical energy, and is free of amplifier tubes.

Another desirable object of my present invention is to provide a novel method of locking in a locked-in oscillator over a greater range for a given amount of injected current.

A further object of my present invention is to provide a passive electrical network across the tank circuit of a locked-in oscillator, the equivalent series capacity of the network being chosen to vary with frequency at just the proper rate to keep the oscillator in tune for a portion of the lock-in range; the added electrical network being the discriminator in an FM receiver if desired.

Still other objects of my invention are to improve generally the efficiency, reliability and range of locked-in oscillators, and more especially to provide locked-in oscillators of extended range which are economical in construction and assembly.

Still other features of my invention will best be understood by reference to the following description, taken in connection with the drawing, in which I have indicated diagrammatically several circuit organizations whereby my invention may be carried into effect.

In the drawings:

Fig. 1 shows the basic locked-in oscillator circuit of the aforesaid Beers patent;

Figs. 1a, 1b and 1c are employed to analyze the circuit action;

Fig. 2 shows one embodiment of my invention;

Fig. 3 shows a more generalized embodiment of my invention;

Fig. 4a shows the resistance and reactance components of the added passive network in Fig. 2;

Fig. 4b shows the equivalent input capacity of the latter;

Fig. 5a shows the oscillator capacity required to keep the oscillator in tune as the frequency is changed;

Fig. 5b shows how to match the added circuit to the oscillator;

Figs. 6a, 6b, 6c and 6d show several circuits that can be used for passive network 35 of Fig. 3;

Fig. 7 shows a modification, wherein the added network of Fig. 2 acts as an FM receiver discriminator; and

Fig. 8 is a circuit diagram of an FM receiver embodying a further modification of the locked-in oscillator.

Referring now to the accompanying drawings, wherein like reference numerals in the different figures designate similar circuit elements, reference is made to the circuit shown in Fig. 1 for an explanation of the fundamental mode of operation of my present invention. In Fig. 1 I have shown a locked-in oscillator which is of the general type shown in the aforesaid Beers patent. The circuit comprises a tube 1 which may be of the pentagrid type. My invention is not limited to such a tube. It will operate with any tube normally used as an oscillator. Between the input grid 2 and the cathode 3 there is impressed high frequency energy of a predetermined frequency F . The plate 4 has connected in circuit therewith a resonant circuit 5 which is tuned to a subharmonic F/n of F , the symbol n denoting a small integer. By way of illustration, the fifth subharmonic may be employed. The plate 4 is, of course, established at a positive potential with respect to the grounded cathode. The second and fourth grids of the tube are connected in common to a source of positive potential, and these grids function as a positive screen grid for the intermediate grid 6.

The latter grid 6 is regeneratively coupled, as at 7, to the plate circuit 5. The fifth grid of tube 1 is connected back to the cathode, and this grid, therefore, functions as a suppressor grid. The cathode 3, grid 6 and plate 4 provide the oscillator section of the circuit. This oscillator section produces oscillations of the subharmonic frequency F/n . These oscillations are continuously produced even in the absence of input energy at grid 2. The oscillations developed across circuit 5 may be transferred to any utilization network.

As shown, the coil 7' has its lower end connected to ground through the resistor 9, and the latter is by-passed for high frequency currents by the condenser 10. This is substantially similar to the locked-in oscillator circuit shown in the aforesaid Beers patent. The current from the tube is not sinusoidal, but comes through as a series of pulses. These cause harmonics of the subharmonic frequency F/n to be developed in the plate circuit 5. These harmonics will be applied to the grid 6 because of the coupling 7. Furthermore, the grid 6 is operating with self-bias, and draws grid current during the positive swings of voltage. These pulses, also, contain harmonics of F/n .

Let us assume by way of illustration that F has a value of 4300 kc. This frequency will beat with the fourth (3440 kc.) and/or sixth (5160 kc.) harmonics of the resonant frequency of the plate circuit thereby to provide the desired subharmonic of 860 kc. In this case it is assumed that the letter n is equal to 5. When the fourth and sixth harmonics are present simultaneously, it can be shown that the result is a single injected current of variable amplitude and phase. The process is similar to that when only one harmonic is present. Usually the fourth and sixth harmonics will be of unequal amplitude, and the effect of the weaker one is to produce relatively small variations in the other. When the frequency of the incoming signal is exactly five times the natural frequency of the oscillator, the harmonic difference component will be in phase with the current in the oscillating plate circuit. The circuit becomes stable in this condition, and the injected current will lock in the incoming 4300 kc. signal with the 860 kc. current in the plate circuit. Since the injected current has the same

phase and frequency as the normal current in the plate circuit it is equivalent to an increased output from the tube.

Now assume for the moment that the incoming frequency is higher than 4300 kc. and is within the lock-in range, but that the oscillator has not yet locked in. The effect of the fourth harmonic will be to inject a current of slightly greater frequency than 860 kc. into the tank circuit. In Fig. 1a, OA is a vector assumed to be rotating 860,000 times per second, and represents the normal current in the oscillator tank circuit. Let AB be a vector representing the instantaneous injected current of frequency slightly greater than 860 kc. resulting from the fourth harmonic of the oscillator voltage beating with the incoming signal voltage. This vector will rotate slightly faster than 860,000 times per second, and thus will have an angular velocity relative to OA equal to the difference of the two angular velocities.

Now consider further the instantaneous condition shown in Fig. 1a. The injected current AB has a component AC, shown dotted, in phase with OA and another component AD (shown dotted) 90° out of phase with respect to OA. The vector OB represents the resultant of OA and AB. Let this current OB be applied to a tuned circuit LC as shown in Fig. 1b. Since the circuit LC is tuned to 860 kc., it will be at resonance with respect to the current OC, which is also 860 kc., and equals $i_a + i_b$. The quadrature current AD is a leading current at the instant shown, and the result is the same as though an additional condenser C' is in the circuit LC. The effect is to decrease the natural frequency of the tuned circuit LC.

Now consider the condition at a later instant, as shown by Fig. 1c, the incoming frequency being the same as in the preceding discussion of Fig. 1a. The oscillator has not yet locked in. The vector AB has rotated to the new position as shown. The injected current AB now has an in-phase component AC as before, but the component AD is now lagging instead of leading. If the current OB is now impressed on the circuit of Fig. 1b, the lagging component AD will cancel part of the leading current through capacity C, and this will be equivalent to reducing the capacity C since it is now drawing a smaller leading current. This will raise the resonant frequency of the tuned circuit LC.

It is now evident that the circuit of Fig. 1 behaves like a reactance tube circuit. It is easy to see that if the frequency of the incoming signal is approximately five times that of the tuned circuit 5, a point will be reached when the frequency of the tuned circuit becomes exactly one-fifth of the incoming signal frequency. When this happens the oscillator will "lock in" with the incoming signal. This means that the amplitude and phase of the plate current now remain fixed with respect to the incoming signal.

If the incoming signal is exactly five times the frequency of the tuned plate circuit, the vector AB will be in phase with OA. As the incoming signal frequency is decreased, the oscillator remaining locked in with it, the vector AB rotates to some position such as that shown in Fig. 1a. A further decrease in frequency will rotate the vector until it is 90° out of phase with respect to OA. Since this position gives the maximum amount of quadrature current it corresponds to the maximum amount that the oscillator frequency can be pulled over, and thus gives the

lower limit of the lock-in range. If the incoming signal frequency becomes greater than five times the plate circuit frequency, the conditions will be similar except that the vector AB will be lagging, as shown by Fig. 1c, instead of leading. The upper limit of the lock-in range is reached when the injected current lags by 90°. The lagging current tends to reduce the effective capacity of the circuit, and thus raises the frequency.

The amount of fourth and/or sixth harmonic current which is applied to grid 6 is limited. This limits the lock-in range of the oscillator, since it limits the amount of the injected current. The result is that when the deviation of the incoming signal from 4300 kc. exceeds approximately 30 kc., the oscillator suddenly breaks out and the frequency goes back towards center. This means that the oscillator is no longer locked in; the ratio of the incoming frequency to the oscillator frequency is no longer a definite small integer. If the oscillator is being used as a secondary frequency standard, to compare two frequencies, to operate a clock, or in an FM receiver, this "break-out" will be objectionable.

In an FM receiver this will cause distortion. The practical operating disadvantage of this "break-out" effect in an FM receiver resides in the fact that if a receiver is mistuned slightly, the "break-out" will occur on one end of the frequency swing and even for normal frequency swings. Such mistuning of a receiver is quite possible, since the average operator of a frequency modulation receiver finds it difficult to tune the receiver exactly. Again, if the FM transmitter station overmodulates, the "break-out" can occur on both ends of the frequency swing.

In accordance with my present invention, the "break-out" effect is substantially eliminated by extending the lock-in range of the oscillator. In general, in accordance with my present invention, and contradistinct from the methods of my aforesaid application, there is provided an auxiliary passive electrical network which is placed in parallel with the tuned plate circuit of the oscillator. This added or auxiliary network is adjusted so that its equivalent input capacity falls off at the proper rate to just keep the oscillator in tune throughout most of the operating range. This makes it possible to lock in the oscillator over a greater range for a given amount of injected current. The passive electrical network does not have any amplifier tubes, and is not a source of electrical energy. The constants of the passive network are so chosen that it has an effective capacity vs. frequency characteristic which falls off at a rate to provide a relatively wide lock-in range for subharmonic frequency oscillations. In Fig. 2 I have shown the present method of extending the range of a locked-in oscillator. The circuit of Fig. 2 is similar in all respects to that of Fig. 1, except for the network now to be described.

The coil 33, resistor 32 and condenser 31 are connected in shunt relation, while the common ungrounded terminals of the three components are connected by condenser 30 to plate 4. Thus, the auxiliary passive network 34 is located in a path to ground parallel to circuit 5. Circuit 34 is tuned approximately to F/n , but in practice may be slightly higher in frequency than F/n . In practice, the circuit 34 of Fig. 2 can be adjusted in several different ways to give the desired capacity variation characteristic. In Fig. 4a, curve a shows the equivalent series resist-

ance of the parallel circuit 34 in Fig. 2 as a function of frequency. The curve is secured by plotting "ohms" against "frequency." Curve b is the equivalent series reactance. The two curves thus show the resistive and reactive components of the impedance of parallel circuit 34 at each frequency. When series condenser 30 is added, if its value is properly chosen, the reactance curve is displaced until it is entirely below the axis as shown by dashed curve b'. The equivalent shunt capacity corresponding to the dashed curve b' of Fig. 4a can be determined from the reactance and frequency, and is shown in Fig. 4b. The equivalent capacity of the added circuit 34 thus decreases with increasing frequency on both sides of the operating frequency F/n of the oscillator.

When this circuit 34 is placed in parallel with the tuned plate circuit 5 of the oscillator, the tank circuit capacity can be reduced slightly and the slope of the capacity-frequency curve (see Fig. 4b) of the added circuit 34 can be adjusted until the capacity decreases at just the proper rate to keep the oscillator circuit 5 in tune for a considerable variation in frequency. In order to keep the oscillator tank circuit in tune over the operating frequency range, the tank circuit capacity should decrease with increasing frequency as shown by Fig. 5a. The slope of this curve is determined by the L/C ratio of the tank circuit. The slope of the curve of Fig. 4b can be matched to that of Fig. 5a over a major portion of the operating range as shown by Fig. 5b. The solid line could represent the falling input capacity of the following discriminator circuit, and the dashed line is the same as in Fig. 5a. When these slopes are matched, the lock-in range will be greatly increased since a small amount of reactive current will shift the oscillator frequency a considerable amount.

In other words, the oscillator can oscillate at any frequency within the range where the falling capacity characteristic of the added circuit 34 matches the rate of change of the plate circuit capacity with frequency required to keep the oscillator in tune. Since the oscillator is in tune for considerable frequency variation, it is easier to lock it in with the incoming signal. The effect is a considerably increased lock-in range. The slope and the distance between the maximum and minimum points of the curve in Fig. 4b can be changed by changing the value of resistance 32 in Fig. 2. Any change in capacity of condenser 30 will, also, cause corresponding changes in the slope of the curve. The operating frequency is approximately F/n , and is selected by proper choice of the inductance of coil 33 and capacity of condenser 31. It should be noted that any variation in the L/C ratio of the plate circuit 5 will, also, change the rate at which the capacity must change with frequency to keep the oscillator in tune. This means that either the L/C ratio of circuit 5 or the constants of circuit 34, or both, can be adjusted until the slopes of the curves (as in Fig. 5b) are the same, or nearly the same, at the operating point.

In Fig. 3 a generalized passive filter network 35 is shown in place of circuit 34. There are many possible electrical circuits that can be used here, the requirement being a resultant input capacity variation with frequency as shown in Fig. 4b. My invention is entirely generic in this regard.

Figs. 6a, 6b, 6c and 6d show respectively different circuits that can be used for network 35 in

Fig. 3. It will be understood that the respective networks of Figs. 6a to 6d could replace generalized network 35 in Fig. 3 between terminals a and b of the latter. In Fig. 6a, the series and parallel resonant frequencies and the circuit Q can be chosen properly so that the equivalent shunt capacity varies in the manner shown in Fig. 4b. In Fig. 6a condenser 36, coil 37 and resistor 38 are connected in series, and condenser 39 shunts the series path. If the capacitor 39 of Fig. 6a is combined with the tank circuit capacity, the series circuit of Fig. 6b will then produce the required conditions. If a coupled circuit, such as 44 in Fig. 6c, is added to the circuit 34 of Fig. 3 it will work properly when the circuits 44 and 34 have a coupling coefficient less than or equal to critical, if the Q of the circuit 34 is greater than or equal to that of circuit 44. In all of these illustrative circuits proposed for use as the shunt auxiliary network, it should be noted that a condenser and resistor in series are substantially equivalent to a condenser and resistor in parallel over a limited frequency range. This means that a series resistor can be changed to a shunt resistor, and vice versa. Fig. 6d shows a circuit equivalent to the circuit of Fig. 6a if the resistor 38 and 38' are properly chosen.

The circuits of either Figs. 2 or 3 can also be combined with the circuits of my aforesaid application to give improved performance. It is, also, possible to design the filter network 35 of Fig. 3 to operate as a frequency discriminator. This permits the detection of frequency modulated signals. It will now be seen that I have provided a novel means for increasing the lock-in range of a locked-in oscillator by adding an electrical network in parallel with the tuned tank circuit, and adjusting the network so that the equivalent input capacity thereof decreases at the proper rate to keep the oscillator in tune throughout the operating range.

It should be noted that when a network is designed so that the oscillator is in tune over a given band of frequencies, the reactance of the oscillator circuit is zero over the same range. This means that the phase angle characteristic is also zero in this range. Therefore, the functioning of the shunt auxiliary network across tank circuit 5 can be alternatively explained in terms of the addition of a network so designed that the phase characteristic of the combination is zero in the desired range.

In Fig. 7 I have shown a method of utilizing the auxiliary network 35 of Fig. 3 for simultaneous discrimination of FM signals and extension of the lock-in range of the oscillator section of a frequency divider. The auxiliary network 34' is still a passive network in this case, since the diodes 17 and 18 function as loads on the network. The system shown in Fig. 7 includes the locked-in oscillator acting as a frequency dividing network in a receiving system of the type disclosed in the aforementioned Beers patent. As more fully explained in the Beers patent the locked-in oscillator functions concurrently to reduce or divide the mean frequency of the applied FM signal waves, and proportionately to reduce the extent of frequency deviation of the waves. Assuming that the FM receiver is of the superheterodyne type and that the networks prior to the locked-in oscillator tube are conventional in nature, the transformer 13 will have its primary circuit 14 tuned to the operating intermediate frequency (I. F.) of the system.

As fully explained in the Beers patent, the

received FM waves are those which are transmitted in the present assigned FM band of 42-50 megacycles (mc.). Of course, the invention is not limited to any particular frequency band or to the reception of FM waves, since it is generally applicable to angle modulated carrier waves. Those skilled in the art are fully aware of the fact that in each channel the FM waves transmitted in the aforementioned assigned FM band are presently allotted a maximum overall frequency swing of 150 kc. with respect to the mean or center frequency F_c . The extent of frequency deviation is dependent upon the amplitude of the modulation signals at the transmitter, while the rate of frequency deviation is dependent upon the modulation frequency per se.

The collected FM waves are selected in one or more stages of tunable radio frequency amplification, after which they are combined with locally-produced oscillations at the first detector network. The output of the first detector or converter is the I. F. (intermediate frequency) energy. In other words, the I. F. energy is the FM wave whose mean frequency has been reduced to a much lower frequency, but whose frequency deviation is unchanged. After amplification by one or more stages of I. F. amplifiers, the I. F. energy is applied to the locked-in oscillator for concurrent frequency division and frequency deviation reduction. Above the I. F. transformer 13 I have depicted, in a purely graphic manner, an idealized response curve of the coupled primary and secondary tuned circuits 14 and 15. It will be seen that the mean frequency is located at 4.3 mc., whereas the pass band of the network is substantially 150 kc. wide. This signifies that the network 14, 15 is capable of efficiently transmitting the entire frequency swings of the FM wave whose mean frequency has been reduced to the operating I. F. value. While the value of 4.3 mc. has been assigned as the operating I. F. value, it is to be clearly understood that any other satisfactory value may be employed depending upon the various factors met with in the design of the receiver.

Since the locked-in oscillator circuits in Fig. 7 are exactly the same as shown in Fig. 2, the same reference numerals are employed. The FM signal energy with its mean frequency at the operating I. F. value is applied to the input grid 2. The input grid 2 is connected to the high alternating potential side of the secondary circuit 15. The low potential side of circuit 15 is returned to the grounded cathode 3 through a resistor and condenser network designated by the numeral 16. The function of the network 16 is to provide voltage across the resistor element in response to grid current flow through the input grid circuit. Such grid voltage developed across the network 16 may be utilized for automatic volume control (AVC). The AVC voltage is employed automatically to bias the control grids of the preceding amplifier tubes in a manner well-known to those skilled in the art.

Above the plate circuit 5 in Fig. 7 I have graphically represented an idealized response curve of the oscillator section output network. It will be noted that it has a pass band width of 30 kc., while the mean frequency has a value of 860 kc. This is appropriate since the effect of the locked-in oscillator network has been to divide the mean frequency of the FM wave energy by a factor of 5, and the over-all frequency deviation range has also been divided by the same factor. Additionally, there is secured a substan-

tial reduction of amplitude modulation effects which may have been created on the FM wave energy in the transmission through space or during the passage of the signal energy through the receiver networks.

This elimination of amplitude modulation effects is secured, as explained in the aforesaid Beers patent, without the use of any special amplitude limiter stage. The advantages of frequency division at this point of the receiving system, have been explained in the Beers patent. The extension of the lock-in range of the oscillator accomplished by this invention as compared with the arrangements shown in the Beers patent will enable reception of waves which are frequency modulated over a wider range and will guard against the distortion which might otherwise occur by reason of the aforementioned "break-out" effect. Since the FM wave energy developed across the plate circuit 5 is modulated in strict accordance with the originally received FM waves, save that the mean frequency and extent of frequency deviation have been proportionately reduced, the output of the locked-in oscillator may now be subjected to suitable discrimination and rectification.

The discriminator employed herein feeds a pair of opposed diode rectifiers 17 and 18. The discriminator network is generally that disclosed and claimed by J. D. Reid in his U. S. Patent No. 2,341,240, granted February 8, 1944. In accordance with my present invention, the discriminator network is given a second and novel function. It acts to extend the lock-in range of the locked-in oscillator. Further analysis of this new function will be given at a later point. The opposed diodes 17 and 18 will be separately fed with signal energy which has the form of amplitude modulated wave energy by virtue of the action of the discriminator which translates the FM wave energy into corresponding amplitude modulated carrier wave energy.

As will be noted from Fig. 7, the output load consists of a pair of series-connected resistors 19 and 20. The junction of the resistors is connected by a return path 21 to the anode of diode 18. The cathode of the diode 18 is established at ground potential. The high potential side of circuit 5 is connected to the anode of diode 17 through the path consisting of condenser 12 and resistor 12' in series. Above the discriminator network I have shown the typical characteristic of an FM detector stage. It will be noted that at the mean frequency F_c the resultant instantaneous output voltage of the detector is zero. The maximum output occurs at the opposite peak limiting frequencies F_1 and F_2 .

Each of the opposed rectifiers includes in circuit therewith its respective load resistor. At the instant when the applied signal energy has the mean frequency value, the rectified voltages across the resistors 19 and 20 are equal in magnitude and opposite in polarity. Hence, the resultant potential at the upper end of resistor 19 is zero. On the other hand the potential at the upper end of resistor 19 will vary in magnitude and polarity depending respectively upon the extent and direction of frequency deviation with respect to the mean frequency. Accordingly, the voltage taken off from the output load of the opposed rectifiers corresponds to the original modulation signal voltage applied to the carrier at the FM transmitter.

The resistor 28 and the pair of parallel condensers 29 to ground provide a de-emphasis net-

11

work whose function is well known in the art of frequency modulation reception. Briefly, the de-emphasis network acts to diminish the response at the higher audio frequencies, since during transmission of the FM waves such higher audio frequency components may have been disproportionately emphasized.

The discriminator circuit in Fig. 7 consists of the coil 33', the resistor 32' and condenser 31' all connected in parallel relation between the anodes of diodes 17 and 18. The constants of network 33', 32', and 31' are chosen so as to extend the lock-in range of the locked-in oscillator. The aforesaid Reid patent describes in detail the manner in which the discriminator circuit acts to translate FM signals into corresponding amplitude variable signals. The low potential side of circuit 34' is connected to ground through the anode to cathode capacity of diode 18, the capacity being indicated by numeral 18' and being shown dotted.

It will be noted in Fig. 7 that the tank circuit 5 is shunted to ground by a network consisting of series-connected condenser 12 and resistor 12' in series with the circuit consisting of coil 33', resistor 32' and condenser 31' all in parallel, and that the latter circuit is connected in series to ground by a circuit consisting of condenser 18' shunted by resistance indicated in dotted lines as 20'. The function of condenser 12 is to couple the discriminator circuit 34' to the tank circuit 5, and also is part of the circuit to extend the lock-in range. Resistor 12' is not always necessary and helps to prevent too much interaction between the oscillator and discriminator due to stray coupling. The shunt resistance of circuit 34' not only includes resistance 32', but should be considered as including approximately one-third of load resistor 19 in parallel therewith. Further, the resistance 20' is equal to approximately one-third of load resistor 20. If resistor 20' and condenser 18' are replaced by an equivalent resistor and condenser in series, and these be respectively combined with 12' and 12, the resultant equivalent circuit would be similar to the auxiliary network 34, 30 shown in Fig. 2. The sole difference would be that in Fig. 7 the condenser 12 would have resistance in series therewith, but, as stated previously, this may be omitted. It will be seen that the discriminator circuit 34' in Fig. 7 thereby acts to increase the lock-in range of the locked-in oscillator in the manner previously explained.

The normal functioning of the discriminator circuit in the manner described by Reid in his aforesaid patent is not interfered with. It is believed sufficient for the purposes of this application to point out that circuit 34' normally has a resonant frequency slightly higher than F/n (860 kc. in Fig. 7). For signal frequencies less than 860 kc. circuit 34' appears to have an inductive reactance having series resistance. As resonance is approached from the low frequency side, the apparent inductance rises very rapidly so that it is possible to obtain series resonance between this inductance and the relatively small capacitance 18' at a frequency close to the parallel resonance. The resultant voltage across the entire network is due to the voltage curves resulting from the series and parallel resonances, the resulting voltage curve having the required spaced maximum and minimum peaks. The spacing of the parallel and series resonances determine the shape of the resultant curve.

The present invention is not restricted to re-

12

ception of frequency modulated signals, but can, also, be used at any fixed frequency. The increased lock-in range is desirable when operating at a fixed frequency to assure that the oscillator will remain locked in even though the circuits may become slightly misaligned due to temperature changes, voltage changes, etc. The use of a locked-in oscillator with a frequency discriminator represents only one application of my invention. It can be used to obtain secondary frequency standards from a given primary standard such as a crystal oscillator. It can be used to compare two frequencies; to operate electronic clocks; or in any other case where a definite ratio of frequencies is desired.

Fig. 8 shows a further modification of the invention, and differs from the system shown in Fig. 7 in that the functions of lock-in range extension and frequency discrimination are separated. The electrical network 35' is shown connected in parallel across tank circuit 5, as in Fig. 3. The characteristic of network 35' is selected to provide the lock-in range extension. The discriminator and detector 40, schematically represented in Fig. 8, is coupled to the tank circuit 5 through an isolation amplifier tube 41. The input electrodes of the isolation tube 41 are coupled across the tank circuit 5. The latter is shunted by resistor 42, and the high potential side of circuit 5 is connected to grid 43 of tube 41 by coupling condenser 44. Resistor 42 adjusts the Q of tank circuit 5. The discriminator-detector 40 may be of any suitable construction. For example, it may be of the aforesaid Reid type, or it can be of the type shown by S. W. Seeley in his U. S. Patent No. 2,121,103, granted June 21, 1938. The arrangement of Fig. 8 makes it possible to provide a desired lock-in characteristic, and also secure a desired discriminator characteristic. It is to be understood that the several forms of networks shown in Figs. 6a, 6b, 6c and 6d can be used at network 35' in Fig. 8. These can be designed to give the desired lock-in range and then adjusted (without affecting the discriminator) to give adjustable adjacent channel selectivity.

While I have indicated and described several systems for carrying my invention into effect, it will be apparent to one skilled in the art that my invention is by no means limited to the particular organizations shown and described, but that many modifications may be made without departing from the scope of my invention.

What I claim is:

1. In combination with a tube provided with at least an electron emitter, a control element, an oscillator grid and oscillator output electrode, means for applying to the control element high frequency current which is angle modulated and has a desired mean frequency, a resonant tank circuit reactively coupled to said oscillator grid and output electrode and tuned substantially to a desired subharmonic frequency of said mean frequency, means including a selective network tuned substantially to said subharmonic frequency, means coupling said selective network to said tank circuit, and said selective network having its constants so chosen that it has an effective capacity vs. frequency characteristic which falls off at a rate to just keep the subharmonic oscillator in tune over most of its operating range.

2. In combination with a locked-in oscillator tube provided with at least an electron emitter, a control element, an oscillator grid and oscillator output electrode, means for applying to the

control element current of a desired frequency, a resonant tank circuit regeneratively coupling said oscillator grid and output electrode and tuned substantially to a desired subharmonic frequency of the input frequency, a network comprising inductance, capacity and resistance all in shunt relation, means coupling said network in parallel across said tank circuit, and the constants of said network being chosen to provide a capacity vs. frequency characteristic which decreases as the frequency increases.

3. In combination with a tube provided with at least an electron emitter, a control element, an oscillator grid and oscillator output electrode, means for applying to the control element current which is frequency modulated and has a desired mean frequency, a resonant tank circuit coupled to said oscillator grid and output electrode and tuned substantially to a desired subharmonic frequency of said mean frequency, an electrical network having a falling capacity vs. frequency characteristic, means connecting said network in parallel across said tank circuit, means for deriving from the frequency modulated current of subharmonic frequency the modulation signals thereof, and an isolation amplifier coupling said tank circuit to said deriving means.

4. In combination with a tube provided with at least an electron emitter, a control element, an oscillator grid and oscillator output electrode, means for applying to the control element high frequency current which is frequency modulated and has a desired center frequency, a resonant circuit coupled to said oscillator grid and output electrode and tuned substantially to a desired subharmonic frequency of said center frequency, a selective network tuned substantially to said subharmonic frequency, means coupling said selective network in parallel to said tank circuit, said selective network having its constants so chosen that it has a capacity vs. frequency characteristic which falls off at a rate to just keep the subharmonic oscillator in tune over most of its operating range.

5. In combination with a tube provided with at least an electron emitter, a control element, an oscillator grid and oscillator output electrode, means for applying to the control element current which is angle modulated and has a desired mean frequency, a resonant circuit coupled to said oscillator grid and output electrode and tuned substantially to a desired subharmonic frequency of said mean frequency, an electrical network having a decreasing capacity vs. frequency characteristic, means connecting said network in parallel across said tank circuit, and means for de-

riving from the angle modulated current of subharmonic frequency the modulation signal thereof.

6. In combination with a tube provided with at least an electron emitter, a control element, an oscillator grid and oscillator output electrode, means for applying to the control element high frequency current which is frequency modulated and has a desired mean frequency, a resonant tank circuit reactively coupled to said oscillator grid and output electrode and tuned substantially to a desired subharmonic frequency of said mean frequency, means including a selective network tuned substantially to said subharmonic frequency, means coupling said selective network to said tank circuit, said selective network having its constants so chosen that it has an effective capacity vs. frequency characteristic which falls off at a rate to just keep the subharmonic oscillator in tune over most of its operating range, and opposed rectifiers including said selective network as a common discriminator input circuit whereby the rectifiers provide an output voltage representative of the frequency modulation.

7. In combination with a tube provided with at least an electron emitter, a control element, a grid and output electrode, means for applying to the control element input current of a desired frequency, a resonant tank circuit reactively coupling said grid and output electrode and tuned substantially to a desired subharmonic frequency of the input frequency, means including a passive selective network tuned substantially to said subharmonic frequency, means coupling said selective network to said tank circuit, said selective network having its constants so chosen that it has an effective capacity vs. frequency characteristic which falls off with increasing frequency at the frequency at which said tank circuit is resonant thereby to provide a relatively wide lock-in range for subharmonic frequency oscillations.
